COMPUTING MACHINE

Walter E. Lippert, Jackson Heights, N. Y., assignor to Underwood Corporation, a corporation of Delaware

Application December 20, 1938, Serial No. 246,856

1 Claim. (Cl. 235—60)

1
This invention relates to computing machines, and more particularly to mechanisms for obtaining true negative totals from a single adding and subtracting totalizer.

It is well known that to obtain such a total on the type of machine illustrated here, it is necessary to introduce a quantity known commonly as a fugitive "1." This fugitive "1" may be introduced in different ways, the one being employed in the present instance operating as follows.

Whenever the totalizer is shifted from its adding position to its subtracting position, 1 is subtracted, and whenever it is returned from its subtracting position to its adding position, 1 is added. By doing this, if a total is taken when the totalizer is in its subtracting position (as is always the case in taking a negative total), the fugitive "1" is properly subtracted without any attention on the part of the operator.

It is also well known that to obtain a negative total without special attention on the part of the operator, it is necessary to have the shifting of the totalizer to its subtracting position controlled automatically by the totalizer (according to its positive or negative condition), this automatic control of the shifting being customarily performed during a blank cycle immediately following the entry of the last item.

In mechanisms of this character it is therefore necessary at times (when the last item was a positive entry, but the total is negative, or vice versa) to shift the totalizer during the blank cycle, the shifting incidentally causing the entry of the fugitive "1."

In many types of machines, the entry of a fugitive "1," or in fact the entry of any amount, may leave the actuating racks or transfer mechanism, or both, in a condition that is not proper for taking a total. It is, therefore, necessary in such machines to operate the machine through a second blank cycle before the total can be taken.

This requirement of two blank cycles prior to the taking of a total has been found very objectionable, especially in types of work necessitating the taking of totals at frequent intervals. It is, therefore, an object of the present invention to relieve this condition by providing a mechanism that will properly condition machines of this character for the taking of a negative total after one, instead of two blank cycles.

With this and incidental objects in view, the invention consists in certain novel features of construction and combinations of parts, the essential elements of which are set forth in appended claim, and a preferred embodiment of which is herein-

2
after described with reference to the drawings which accompany and form part of the specification.

In the drawings:

5 Figure 1 is a perspective view of a computing machine embodying the invention,

Figure 2 is a diagrammatic view of the keyboard thereof,

10 Figure 3 is a right side elevation of the totalizer and the fugitive "1" entering mechanism, showing the position of the parts immediately following the insertion of the fugitive "1,"

15 Figure 4 is a view similar to Figure 3 but with the parts restored by certain restoring mechanism that is operable at the beginning of a total cycle,

Figure 5 is a right side elevation showing the totalizer engaged and the train of mechanism for momentarily disengaging the totalizer at the beginning of a total cycle,

20 Figure 6 is a view similar to Figure 5 but with the parts shown operated and the totalizer disengaged,

Figure 7 is a fragmental perspective view of the 25 mechanism for automatically conditioning the totalizer to take a negative total,

Figure 8 is a fragmental perspective view of the 30 rack and pawl restoring mechanism operable at the beginning of the total cycle, and showing the connection between this mechanism and the blank cycle enforcing mechanism, and

Figure 9 shows a portion of a tally strip illustrating the type of work accomplished by the machine.

GENERAL DESCRIPTION

The invention is herein exemplified in connection with mechanism of the general character disclosed in the U. S. Patents No. 1,198,487, issued to Gustaf D. Sundstrand, and Nos. 1,583,102, 40 1,965,611, 2,004,495 and 2,088,982, issued to Oscar J. Sundstrand.

On this class of machine, accumulating operations are performed by indexing in the keyboard the amount that is to be listed and accumulated, and starting the machine by depressing the Motor bar. Stops set by the amount keys arrest the type bars during their upward movement in positions wherein the numeral type corresponding to the amount indexed is in position to print. Adding and subtracting racks carried by the type bars are arranged for movement therewith.

Prior to the up-stroke of the racks in an accumulating cycle, the totalizer is moved to a neutral position intermediate the two sets of racks, and just prior to the down-stroke of the racks the

totalizer is engaged with whichever set of racks is to be used in the accumulating operation.

An enforced blank cycle prior to a total cycle insures the resetting of any transfer pawls which may have been tripped during the preceding accumulating cycles, and automatically engages the totalizer with the proper set of racks in accordance with the positive or negative character of the total to be taken.

During the total cycle, the totalizer wheels are in mesh with the selected set of racks during the up-stroke of the latter. Therefore, as the transfer lugs carried by the wheels abut the under side of their associated transfer pawls, their corresponding type bars are arrested in position for printing the totals which have been accumulated in the totalizer.

Since an error of "1" occurs whenever the totalizer overdraws, a means must be provided to correct this error. This means includes a tumbler arranged to be oscillated alternately clockwise and counter-clockwise, as the totalizer shifts from one set of racks to the other. Such movement of the tumbler causes it to trip a pawl associated with the units order rack of the set of racks engaged, whereby the units rack is permitted to descend a distance of one tooth to additively or subtractively accumulate, as the case may be, the fugitive "1" in the units wheel.

In the ordinary course of operations, this accumulation of the fugitive "1" trips one or more transfer pawls and actuating racks that are not restored until the next cycle. Further, it may happen that the amount of the last item of a group to be totaled is of opposite character to, and less than the aggregate amount of the preceding accumulated items. Under such a condition, when the machine is operated through the blank cycle to condition the totalizer for taking a total, the movement of the totalizer from one set of racks to the other causes the fugitive "1" pawl to trip and thereby introduce the necessary fugitive "1" as in the normal course of operations, but, since the entry of the fugitive "1" leaves one or more parts out of normal position, another blank cycle is necessary before the total can be taken.

To obviate the necessity of two blank cycles before taking a total, there is provided an independent rack and stop pawl restoring means. This means is arranged to be controlled by the mechanism for enforcing the blank cycle, and upon operation of the latter, the means becomes effective to disengage the totalizer from the racks, raise the descended units rack, restore the associated stop pawl, and re-engage the totalizer at the beginning of the ensuing total cycle. Hence, the accumulation of the fugitive "1" is completed at the very beginning of the total cycle, and before the type bars have started to rise.

DETAILED DESCRIPTION

INDEX OF TOPICS

1. The machine sections and actuating mechanism generally.
2. Mechanism for shifting the totalizer.
3. Transfer mechanism generally.
4. Fugitive "1" entering mechanism.
5. Mechanism for enforcing a blank cycle prior to the taking of a total.
6. Automatically conditioning the totalizer for taking a negative total.
7. Mechanism for restoring racks and stop pawls at the beginning of a total cycle.

1. The machine sections and actuating mechanism generally

Referring to Figures 1 and 2, the machine includes the usual keyboard 1 having amount keys 2, a Subtract key 3, Non-add key 4, Total key 5, a carriage 6 supporting a platen 7 around which the paper is guided, type bars 8 for printing on the paper, a motor 9 and a Motor bar 10.

Type bars 8 are suitably guided for vertical movement and are individually raised and lowered by arms 11 (one being shown in Figure 3) carrying headed studs that lie in elongated openings 12 in the type bars. The arms 11 are pivoted on a shaft 13, and have springs such as 14 connected to their rear-most ends to raise such of the bars as are free to rise as the machine operates. A rod 15 extends transversely across the forward ends of arms 11 and is arranged to control the upward and downward movement of the type bars through the action of cam plates such as 16 connected to the opposite ends of rod 15. Each cam plate 16 has a cam slot 17 into which projects a stationary roller 18 secured on the machine side wall. The rear end of each plate 16 is provided with a recess 19 in which lies a roller such as 20 mounted on stud 21 fixed in a lever 22 pivoted on a stationary stud 23 secured in the machine frame. Links such as 23a are connected to studs 21 and studs such as 24, fixed in the crank arms 25 secured to an actuating shaft 26.

The machine is actuated by a motor 9 (Figure 1). The motor is started by the closing of a suitable switch, and is coupled with the actuating shaft 26 by a suitable clutch upon depression of Motor bar 10. The actuating shaft is coupled with the motor drive in such manner that it is rocked, first, counter-clockwise (Figure 3) and then clockwise, about 90° during each cycle of the machine. Hence, as crank arms 25 swing upwardly during the first part of the cycle, levers 22 are swung clockwise about studs 23, and cam plates 16 in turn are moved upwardly, raising rod 15 and thereby permitting arms 11 to raise type bars 8 under the tension of springs 14. During the second half of the cycle, as crank arms 25 swing clockwise, a reverse movement of the parts takes place, i. e., levers 22 are swung counter-clockwise, cam plates 16 are moved downwardly, pulling rod 15 downwardly and thereby restoring the type bars. The foregoing train of parts and their operation is identical with the similar parts disclosed in the aforementioned Patent No. 1,965,611, except that the upper portion of cam slots 17 are provided with longer dwells than the cam slots 33 in cam plates 32 of that patent, whereby type bars 8 are delayed somewhat from upward movement at the beginning of the cycle for a purpose which will hereinafter be explained.

Each type bar 8 carries a pair of depending actuating racks 27 and 28 (Figure 3) lying on opposite sides of a totalizer indicated generally at 29. The totalizer includes a plurality of wheels 30 journaled on a shaft 31. Shaft 31 is arranged to be shifted horizontally to engage wheels 30 with either of the sets of racks. Racks 27 are effective to rotate the wheels in a clockwise direction for accumulation of additive amounts, while racks 28 rotate the wheels in a counter-clockwise direction for the accumulation of subtractive amounts. Normally, the wheels are engaged with adding racks 27. When an item indexed on keys 2 (Figure 1) is to be added, wheels 30 are moved to neutral position (shown in Figure 4) between the two sets of racks, before type

bars 8 are raised to print the item. The wheels are moved back into engagement with racks 27 just before the bars are moved downwardly. Addition, therefore, is accomplished on the down-stroke of the racks. The extent of rotation of wheels 30 is controlled by the extent of rise of the type bars in accordance with the amount indexed.

Depression of Subtraction key 3 following the indexing of an item causes the wheels to be moved from neutral position into engagement with subtraction racks 28 just before the latter descend, whereby subtraction of the item is accomplished on the down-stroke.

To take a total, the Total key 5 is depressed and the machine operated. During this operation, wheels 30 are engaged with the set of racks selected during the blank cycle preceding the total cycle, so that during the upstroke of the racks, the total is cleared from the wheels. They are withdrawn from engagement with the racks just before the racks descend, and are re-engaged at the very end of the operation.

Depression of Non-add key 4 causes wheels 30 to be held in neutral position during both the ascent and descent of the racks, so that an item may be printed without accumulating it on the totalizer.

All of the before-mentioned features are common to the Sundstrand patents mentioned in the foregoing (with the minor exception of cams 16 hereinbefore noted) and to which reference may be had for a more detailed description.

2. Mechanism for shifting the totalizer

The mechanism for moving wheels 30 into and out of mesh with racks 27 and 28 to accomplish the operations above outlined, is identical with that disclosed in the previously mentioned Patent No. 1,965,611. A pair of links, such as 32 (Figures 5, 6 and 7), are pivoted at their forward ends to the opposite ends of shaft 31. The rear ends of links 32 are pivoted as at 33 to the lower ends of two levers, such as 34, fixed to a shaft 35 journaled in the framework of the machine. When levers 34 are in the position shown in Figure 7 (only the right lever being shown), wheels 30 are in mesh with adding racks 27.

The means for swinging levers 34 to move the wheels into and out of mesh with the racks comprises a link 36 (Figures 5, 6 and 7), the forward end of which is supported by a lever 37 pivoted on a stud 38. The rear end of link 36 is provided with notches 39 and 40 to receive pins 41 and 42, respectively, on the opposite ends of the right hand lever 34. Rearwardly of notches 39 and 40 are lugs 43 and 44, respectively, which serve to prevent disengagement of lever 34 from link 36. Forwardly of notches 39 and 40 are curved surfaces arranged to slide in contact with pins 41 and 42. Link 36 is moved forward and back by a cam plate 45 (Figures 5 and 6) having a cam slot 46 therein, the upper portion of the slot being concentric with the axis 47 of the plate. The forward end of link 36 carries a roller 48 that lies in slot 46. Cam 45 is oscillated about its axis 47 on each cycle of the machine by a reversible pawl mechanism (not shown) having connection with actuating shaft 26 (Figure 3), as fully disclosed in Patent No. 1,965,611. By provision of the above mechanism, as cam 45 swings upwardly during the first half of the cycle, link 36 is drawn forwardly, and levers 34 are swung clockwise about shaft 35, as viewed in Figure 7, whereby

wheels 30 are withdrawn from engagement with racks 27 before the latter rise; and when cam 45 swings downwardly, during the latter half of the cycle, link 36 is thrust rearwardly, whereby levers 34 are rocked counter-clockwise of shaft 35, bringing wheels 30 into engagement with racks 27 before they descend.

Link 36 is connected with Subtraction key 3 by a lever 49 (Figure 7) pivoted on the machine frame at 50. Lever 49 is provided at its rear end with a recess 51 embracing a pin 52 on link 36, and has a downwardly extending arm 53 carrying a pin 54 that lies in a slot 55 in a slide 56. A spring 57 connected between slide 56 and lever 49 normally tensions the pin against the rear end of the slot. The forward end of slide 56 is pivoted to a depending arm of a lever 58 pivoted on a stud 59. Lever 58 has a forwardly extending arm 60 underlying a pin 61 fixed in a plate 62 secured to the stem of Subtraction key 3. A spring 63 connected between plate 62 and the machine frame normally tensions key 3 upwardly, and a spring 64 connected between the lower arm of lever 58 and the machine frame normally tensions the lever clockwise about stud 59 so that arm 60 rests against pin 61. When the parts are in the normal position shown in Figure 7, tension of spring 64 urges slide 56 forwardly and causes lever 49 to hold notch 40 of link 36 in engagement with pin 42.

When an amount is to be subtracted, depression of key 3 rocks lever 58, which in turn thrusts slide 56 rearwardly, moving the rear end of slot 55 away from pin 54 and tensioning lever 49 upwardly.

Now when levers 34 are rocked clockwise at the beginning of the cycle, notch 39 is brought opposite pin 41, whereupon lever 49 thrusts link 36 upwardly, engaging notch 39 with pin 41 and disengaging notch 40 from pin 42.

Hence, as cam 45 (Figure 6) rocks downwardly at the beginning of the second half of the cycle, levers 34 are rocked further clockwise about shaft 35 instead of counter-clockwise, engaging wheels 30 with subtraction racks 28 (Figure 5) instead of adding racks 27.

A latch indicated at 65 (Figure 7) is provided to maintain lever 58 and its associated parts in operated position to effect this result. At the completion of the cycle, latch 65 is released, allowing the parts to return to their normal positions.

If, on the ensuing cycle, key 3 is again depressed, wheels 30 are disengaged from racks 28 at the beginning of the cycle and remain in such position during the ascent of the racks, re-engaging the racks just before the descent thereof. If key 3 is not depressed, link 36 ceases to be tensioned upwardly. Hence, at the beginning of this cycle, notch 40 re-engages pin 42 as notch 39 disengages from pin 41, whereby wheels 30 are engaged with racks 27 instead of racks 28 during the last half of the cycle.

As described in Patent No. 1,965,611, the reversible pawl mechanism (not shown) does not disengage the totalizer at the beginning of a total taking cycle. The totalizer, therefore, remains engaged (except for a brief interval later referred to) with the set of racks with which it was left engaged at the completion of the blank cycle, to set up the total on the type bars and return the totalizer to zero. At the beginning of the second half of the cycle, the totalizer is disengaged from the racks if a final total is de-

sired, and is again engaged at the very end of the cycle. If a sub-total is desired, the totalizer is allowed to remain engaged during the entire second half of the cycle.

3. Transfer mechanism generally

Referring to Figures 3 and 4, the sets of racks 27 and 28 are connected to type bars 8 by individual pin-and-slot connections that permit one step of downward movement of each rack relative to its type bar. The racks are guided for vertical movement in slots 66, formed on inwardly facing surfaces of a pair of similar bars 67 which extend longitudinally of the totalizer and which are supported in the machine frame.

Each rack is provided with a lug 68 which moves in the vertical plane of its respective bar 67, and which is arranged to be arrested by the bar to define the lowermost position of the racks.

Two rods 69 are supported in the machine frame at opposite sides of the two sets of racks, and operatively support a plurality of stop pawls 70, one such pawl being provided for each rack. Each pawl 70 is formed with a lug arranged to co-act with lugs 68 on their respective racks, to support the latter one step of movement above bars 67. To the lower end of each pawl 70 is pivoted a dog 71, having a tooth 72 engaging the edge of the adjacent bar 67.

Each of the wheels 30 has two diametrically opposed lugs 73 fixed to one side thereof (see also Figure 7) and which are arranged to disengage the teeth 72 from the bars 67. When an amount registered by a wheel reaches nine, continued rotation of that wheel as its rack descends brings one of the lugs 73 against the upper edge of the end of the dog 71 associated with the next higher order rack, thereby depressing the dog until its tooth 72 is clear of the bar 67, whereupon a spring 74 (assisted by the downward pressure of a spring 75^a of the said next higher order rack) moves the dog and pawl 70 away from the higher order rack, the latter then being free to drop the one tooth space, where it is stopped by contact of its lug 68 with bar 67.

Any transfer elements that are tripped during one cycle of the machine are normally restored during the next cycle. The pawls 70 and dogs 71 are restored by a pair of rods 75 lying adjacent the dogs 71. Each rod 75 is supported by two bellcrank levers, such as 76, pivoted on rods 69. The bellcrank levers are connected for simultaneous swinging movement by a pin-and-slot connection 77. The rods 75 are simultaneously moved toward and away from their associated dogs 71 by operation of two arms, such as 78, that are formed integrally with the right hand set of bellcrank levers 76. A rod 79, lying in the transverse plane of arms 78, is arranged for downward movement (as indicated by arrow) during the first half of each machine cycle. Such downward movement of this rod causes it to abut arms 78 and thereby rock bellcrank levers 76 about their pivots to swing rods 75 inwardly, as shown in Figure 4, to restore any pawls 70 and dogs 71 that have been tripped. This restoring action takes place at a point in the machine cycle where any dropped type bars will have been raised, so that their lugs 68 are above the lugs on pawls 70 when the latter are restored.

This construction is common to the Sundstrand patents previously mentioned.

4. Fugitive "1" entering mechanism

As previously stated, whenever a totalizer of

the type used in the present construction is changed from a positive to a negative condition, or vice versa, an error of "1" occurs in the accumulated total. To correct this, mechanism is provided to enter "1" in the units wheel 30 every time the totalizer is shifted from the adding racks to the subtracting racks, or vice versa, so that when a total is taken by one or the other set of racks, the fugitive "1" will have been entered. This mechanism includes a tumbler 80 (Figures 3 and 4) which is rotatably mounted on shaft 31 immediately adjacent the units order wheel 30. Tumbler 80 is provided with oppositely disposed lugs 81, arranged to engage dogs 71 that are connected with the pawls 70 associated with the units order racks 27 and 28.

A pair of stationary pins 82 are held by the machine frame on opposite sides of an upward extension of tumbler 80. Movement of the totalizer from engagement with subtraction racks 28, as shown in Figure 3, past neutral position, as shown in Figure 4, and into engagement with adding racks 27, as shown in Figure 7, causes a beveled edge 83 on the tumbler to abut the right hand pin 82, and thereby cam the tumbler clockwise about shaft 31 a distance sufficient to cause lug 81 to release dog 71 from engagement with bar 67. This allows the units rack 27 to descend a distance of one tooth to additively introduce the fugitive "1" in the units order wheel 30. Upon shifting totalizer 29 from engagement with adding racks 27, as shown in Figure 7, past neutral position and into engagement with subtracting racks 28, as shown in Figure 3, a beveled edge 84, similar to 83, abuts the left hand pin 82, and thereby cams tumbler 80 counter-clockwise about shaft 31, to cooperate with dog 71 in entering the fugitive "1" subtractively in the units order wheel 30.

40 A flat spring detent 85, suitably mounted in the totalizer frame, is arranged to engage spaced notches in the upper extension of tumbler 80 to hold the tumbler in either of its moved positions. It will be observed with reference to Figure 4 that the movement of totalizer 29 from engagement with either of the sets of racks to merely neutral position does not impart any movement to tumbler 80, since this amount of movement of wheels 30 from either of the sets of racks is insufficient to cause either of the beveled edges 83 and 84 to be cammed downwardly by the stationary pins 82. The accumulation of a fugitive "1" which has been introduced as above described is completed on the ensuing cycle when the tripped stop pawl 70 and its associated dog are restored by the transfer restoring mechanism described in the preceding section.

5. Mechanism for enforcing a blank cycle prior to the taking of a total

This machine is equipped with a mechanism similar to that described in the afore-mentioned Patent No. 1,583,102 for enforcing a blank cycle prior to the taking of a total. The purpose of this mechanism is to insure restoration of any tripped transfer pawls before the total is taken, and also to engage the totalizer with either the adding or subtracting racks in accordance with the character of the total.

The blank cycle mechanism comprises a detent plate 86 (Figure 8) guided to move forward and rearward in a horizontal plane, said plate being pivotally connected at 87 to a frame 88. Frame 88 is mounted, for its limited swinging

movement, upon a stationary rod 89 fixed in the machine frame, and is normally urged forward by springs such as 90.

A plate 91 pivoted in the machine frame at 92 is provided with a lug 93. A forwardly projecting lug 94 on detent 86 is continually held in contact with lug 93 through the action of springs 90. Whenever any one of the numeral keys 2 is depressed to set up the first digit of an item, detent plate 86 is pushed back to prevent pins 95 carried by the type bars 8 to the left of the set up number from rising. This result is effected by a lever 96 pivoted in the framework of the machine at 97, the front end of lever 96 bearing against a universal bail 98 arranged to be rocked by depression of any of the keys 2 by suitable connections similar to the one shown.

Detent plate 86 is held in its rearward position against the tension of springs 90 by a latch 99 pivoted at 100 and held in contact with plate 91 through tension of a spring 101.

During a blank cycle, a means for removing detent plate 86 from above the type bar pins 95 becomes effective. This means comprises a lever 102 pivoted at 103 to plate 91 and having an extension 104 which lies in the path of a projection 105 fixed on one of the crank arms 25 on actuating shaft 26. When the extension 104 is struck by the projection 105, plate 91 is forced forward away from detent plate 86, thereby releasing the latter to the action of springs 90.

In order that projection 104 shall not release detent 86 to the action of springs 90 during the entering of an item, but only during a blank cycle, extension 104 is made movable into and out of the path of movement of projection 105, under control of amount keys 2 by the following parts.

An arm 106 of lever 102 is arranged to abut a lug 107 formed on a slide 108 through which the upstanding pins 95 of type bars 8 are guided. A spring 109 tends to move lever 102 in the direction to lower extension 104 out of the path of movement of projection 105. When slide 108 is in its initial position, extension 104 is held up in the path of movement of projection 105. However, when a digit is set up by depression of a numeral key 2, the resulting movement of slide 108 (through suitable escapement mechanism not shown) allows extension 104 to be lowered by spring 109 out of the path of movement of projection 105, so that plate 91 is not moved forward during that cycle. When slide 108 is returned to its initial position at the end of the cycle, however, extension 104 is raised into the path of projection 105 so that if the next cycle is a blank cycle, extension 104 is struck by projection 105 and moves plate 91 forward, allowing plate 86 also to move forward to condition the machine for the taking of a total.

This mechanism is substantially identical with that disclosed in Patent No. 1,583,102.

6. Automatically conditioning the totalizer for taking a negative total

A mechanism similar to that disclosed in Patent No. 2,088,982 is provided in this machine to insure the engagement of the totalizer with subtracting racks 28 during the blank cycle, in the event that the totalizer has become overdrafted, i. e., the credit amounts accumulated have exceeded the debit amounts.

This mechanism includes a bail 110 (Figure 7), the upper and lower arms of which are pivoted on studs 111 secured in the machine frame. The 75

upper arm of the bail has a universal connection with lever 22 whereby, as this lever is swung to and fro about stud 23 during each cycle of the machine, it imparts a slight oscillatory movement to bail 110. The lower arm of the bail carries a yielding projection 112 arranged to lie directly in front of a stud 113 fixed in slide 56, whenever the bail is elevated a slight distance on studs 111. The means for so elevating bail 110 comprises a bellcrank 114 pivoted on a stud 115 and having a horizontal arm 116 underlying a pin 117 secured to the bail. A vertical arm 118 of the bellcrank has an inturned flange 119 that normally, during each cycle of the machine, abuts a stop lever 120 pivoted as at 121 in the machine frame. A link 122 (No. 1076 in Patent No. 2,088,982) pivoted on a stud 123 secured in arm 118 has connected thereto a spring 124 which tensions flange 119 toward stop lever 120.

20 The rear end of lever 120 is forked, and embraces a pin 125 fixed in an extension 126 of a plate 127 mounted for pivotal movement on a rod 128 supported in the machine frame. The upper edge of plate 127 is embraced by a forked end of 25 a link 129, which is connected by pin-and-slot connections with arms 130 pivoted on rods 69. Each arm 130 is provided with a dog 131 similar to the dogs 71, and which are arranged to be disengaged from bars 67 by lugs 73 of the totalizer wheel 30 of highest order.

30 A roller 132 on the lower end of lever 22 is arranged to bear against a flange 133 provided on arm 118 of bellcrank 114 and holds flange 119 a short distance away from stop lever 120 when lever 22 is in the normal position shown. When an amount accumulated in the totalizer represents a debit balance, the parts are in the position shown in Figure 7. However, when the totalizer is overdrafted, the wheel 30 of highest order passes through zero, causing lug 73 to trip dog 131 on the subtract side of the totalizer, and to swing arm 130 clockwise about rod 69 under tension of spring 74. This movement thrusts link 129 toward the right as viewed in Figure 7, rocks plate 127 clockwise about rod 128, and swings stop lever 120 downwardly about its pivot 121, out of the path of flange 119. Now, if a blank cycle is taken to condition the machine for a total operation, bellcrank 114 is free to swing clockwise about stud 115 as roller 132 moves away from flange 133 at the beginning of the cycle. This permits arm 116 to elevate bail 110, bringing projection 112 into the plane of stud 113.

55 Clockwise oscillation of bail 110 then causes the projection to abut stud 113 and thrust slide 56 rearwardly to tension lever 49 upwardly. Hence, when levers 34 rock clockwise following the above described movement of the parts, notch 39 of link 60 36 engages pin 41 in the same manner as previously described. Therefore, wheels 30 are placed in engagement with the subtraction racks 28 (Figure 3) at the beginning of the last half of the cycle, preparatory to the taking of the negative 65 total on the succeeding cycle. At the end of the blank cycle, roller 132 strikes flange 133 and rocks bellcrank 114 counter-clockwise to its normal position.

Mechanism similar to that disclosed in Patent 70 No. 2,088,982 is provided on the forward end of link 122 to prevent the link from coming forward when an amount is indexed in the keyboard, so that even though stop lever 120 is lowered out of the path of flange 119 by virtue of the presence of a negative balance in the totalizer, the latter

will not be automatically engaged with the subtraction racks for the accumulating operation.

7. Mechanism for restoring racks and stop pawls at the beginning of a total cycle

The automatic shifting of the totalizer from one set of racks to the other in accordance with the nature of the total to be taken occurs during the blank cycle as above described, and causes tumbler 80 to trip the fugitive "1" pawl of the set of racks engaged, to correct the error of "1" as described above. However, since this insertion of the fugitive "1," like an ordinary transfer from one order to the next, leaves one or more of the actuating racks and transfer dogs out of normal position, a second blank cycle must be taken before the total, unless some other means is provided to restore these parts.

A means to restore these parts without requiring the second blank cycle is provided in the present mechanism, and is rendered effective by actuation of the blank cycle mechanism, to restore the parts at the very beginning of the total cycle. In operation, this mechanism withdraws totalizer 29 from engagement with the racks, raises the descended units rack and any other racks which may have descended by virtue of transfer, restores their respective tripped stop pawls and re-engages the totalizer with the set of racks from which it was disengaged, at the beginning of the total cycle and before the type bars and racks start to rise to print the total.

The mechanism includes a lever 134 (Figure 8) pivoted on a stud 135 fixed on a plate 136. Plate 136 is pivoted on a stud 137 on the machine frame, and has a cam edge 138 against which rides a roller 139 secured on the left crank arm 25. A spring 140, connected between plate 136 and the machine frame tensions edge 138 against roller 139. During each cycle of the machine, crank arm 25 swings plate 136 upwardly raising lever 134. As crank arm 25 returns to its initial position shown in Figure 8, plate 136 restores under tension of spring 140, and lever 134 likewise descends to the position shown. A spring 141 connected between lever 134 and plate 136 normally tensions the lever clockwise (as viewed in Figure 8) about stud 135, and causes a hook 142 formed on the lower end of the lever to embrace one of the four pins 143. The upper end of the lever lies in the path of a projection 144 on detent 86. When an amount is indexed on amount keys 2 and detent 86 is thrust rearwardly, projection 144 strikes the upper end of lever 134 and rocks the lever counter-clockwise (as viewed in Figure 8) so that hook 142 is ineffective to engage pins 143. During a blank cycle, as detent 86 and projection 144 move forwardly, the upper end of lever 134 follows the projection under the tension of spring 141, causing hook 142 to engage one of the pins 143. Pins 143 are fixed on a disk 145 secured on one end of a shaft 146 suitably journaled at its opposite ends in the machine frame.

A pair of four-point cams 147 and 148 are fixed on shaft 146 on opposite sides of a link 149 (Figures 5 and 6), with their points arranged in offset relation as shown. Link 149 is provided with a slot 150 to accommodate shaft 146, and carries an inwardly projecting pin 151 arranged to be engaged by the points of cam 147, and an outwardly projecting pin 152 arranged to be engaged by the points of cam 148. The opposite end of link 149 is pivoted at 153 to a cam lever 154 loosely journaled on actuating shaft 26.

Cam lever 154 is provided with a slot 155 embracing a roller 156 secured on cam plate 45.

When hook 142 is engaged with one of the pins 143, upward movement of plate 136 causes the hook to rotate shaft 146, 90°. During this movement, one of the points of cam 148 bears against pin 152 and thrusts link 149 toward the right to the position shown in Figure 6. This movement rocks cam lever 154 counter-clockwise to rotate cam plate 45 counter-clockwise, a distance sufficient to cause link 36 to withdraw totalizer 29 to neutral position as shown in Figure 6. It remains in this position for an instant, after which one of the points on cam 147 strikes pin 151 and moves link 149, lever 154, plate 45 and link 36 back to their initial positions shown in Figure 5, to re-engage the totalizer with the set of racks from which it has just withdrawn.

This movement of shaft 146 occurs at the very beginning of the total cycle, and sufficient time is provided for its completion before the type bars are raised to lift the racks. This time is provided by provision of extra length in the dwell in cam slot 17 (Figure 3) in plates 16, as referred to in an earlier part of the specification.

While the totalizer remains momentarily in the neutral position as shown in Figure 6, a second pair of four-point cams 157 (Figures 3, 4 and 8), secured on shaft 146, raise any dropped racks and restore any tripped stop pawls in the following manner. A pair of bails 158 and 159 (best shown in Figure 8) are pivoted on stationary rods 160, and each carries a transversely extending rod 161 located directly under the sets of racks 27 and 28 at a distance beneath the racks sufficient to permit one step of downward movement thereof. The inner ends of the bails are pivotally connected to each other by pin-and-slot connections. Bail 158 carries a pair of inwardly projecting studs 162 arranged to be engaged by the points of cams 157. A pair of arms 163 pivoted on a stationary rod 164 are provided with cam slots 165 embracing a rod 166 carried by bail 159. The upper ends of arms 163 have pivotally mounted thereon a pair of yielding projections 167 arranged to bear against the rear stop pawl restoring rod 75 (see also Figure 3). While totalizer 29 is momentarily disengaged, during the 90° movement of shaft 146, a pair of the points of cams 157 bear against studs 162 and cam bails 158 and 159 upwardly from the position shown in Figure 3 to the position shown in Figure 4. This movement causes rods 161 to restore any dropped rack (rack 28 in Figure 3) so that its lug 68 is above the plane of the lower end of stop pawl 70. At the same time, arms 163 are rotated counter-clockwise as viewed in Figures 3 and 4, by virtue of their cam slot connections with rod 166, causing projections 167 to thrust restoring rod 75 inwardly toward the racks, as shown in Figure 4; to restore the tripped dogs 71 and stop pawls 70. In this manner, the parts used in entering a fugitive "1" in the totalizer during a blank cycle are restored to normal position before the type bars and racks rise during a total taking operation.

A spring pulled detent 158 (Figures 3 and 4) is pivoted at 167' in the machine frame, and carries at its lower end a roller 169 engaging notches in disk 145, to prevent improper rotation of shaft 146.

While the form of mechanism herein shown and described is admirably adapted to fulfill the objects primarily stated, it is to be understood that it is not intended to confine the in-

vention to the one form of embodiment herein disclosed, for it is susceptible of embodiment in various forms all coming within the scope of the claim which follows.

What is claimed is:

In a calculating machine having cycling mechanism, a totalizer, sets of actuators respectively at opposite sides of said totalizer, means for shifting the totalizer into engagement with one or the other of said actuator sets and to a neutral position between them, a mechanism operable to effect tens-transfers by an extra step of movement of said actuators, total-taking control means, and means operated by said cycling mechanism prior to total-taking for moving the totalizer to neutral position and restoring actuators that have been moved an extra step; the combination with the foregoing of supplemental means for restoring actuators that have been moved an extra step when the totalizer moves from one set of actuators to the other in conditioning the machine for total-taking, comprising movable means positioned opposite the actuators, a rotatable member having cams, a connec-

tion from said rotatable member to said means for shifting the totalizer from one set of actuators to the other, means preventing rotation of said rotatable member except when said total-taking control means operates to condition the machine for total-taking and enabling rotation of said member to cam-operate said connection and said movable means upon subsequent cycling of the machine.
